CLAIM

The ornamental design for a robotic toy base, as shown and described.

DESCRIPTION

FIG. 1 is a top perspective view showing a first embodiment of the robotic toy base;

FIG. 2 is a left side view of FIG. 1;

FIG. 3 is a right side view of FIG. 1;

FIG. 4 is a front side view of FIG. 1;

FIG. 5 is a back side view of FIG. 1;

FIG. 6 is a top side view of FIG. 1;

FIG. 7 is a bottom side view of FIGS. 1; and,

FIG. 8 is a bottom back side perspective view of FIG. 1.

The broken lines are for the purpose of illustrating portions of the environmental structure and forms no part of the claimed embodiment and design.
